UNITED STATES PATENT OFFICE.

HENRY BEHM, OF JERSEY CITY, NEW JERSEY.

VIBRATOR.

1,025,236.

Specification of Letters Patent. Patented May 7, 1912.

Application filed February 2, 1912. Serial No. 675,044.

To all whom it may concern:

Be it known that I, HENRY BEHM, a subject of the Emperor of Germany, residing at Jersey City, in the county of Hudson and State of New Jersey, have invented certain new and useful Improvements in Vibrators; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention relates to an improved vibrator which consists of a suitable holder which has a vibratory element thereon, the vibratory element being normally at rest, being set in vibration by the impact of a stream of fluid, preferably water.

The preferred form of vibrator comprises a holder with a cup-shaped part which encloses a nozzle for directing the stream of water against the vibratory element, the element being repeated so that there is a series of them. The nozzle is arranged to submit each element to an intermittent contact with the stream, this being best accomplished by a rotary nozzle with an outlet for directing a stream against the element in rapid succession.

The invention further comprises an adjusting means for regulating the relative positions of the nozzle and the vibratory elements so that the amount of vibration with a given stream can be controlled by the location of the point of impact of the stream.

The invention is illustrated in the accompanying drawing, in which—

Figure 1 is a vertical section of my new vibrator showing the handle portion and the nozzle in elevation. Fig. 2 is a detail of a modified form of vibratory element. Fig. 3 is a section of a modified form of construction taken on line 3, 3, in Fig. 4, and Fig. 4 is a longitudinal section of the same modification.

The device comprises a holder which is provided with a handle portion 10 which is conveniently disposed, being preferably made as shown in the drawing, that is, it is

at right angles to the main part of the holder so that the vibrating portion can be applied to any portion of the body by the person using it, being especially for use over the shoulders so as to get in contact with the back and the spinal cord. A suitable pipe 11 is adapted to conduct the fluid, the pipe having a suitable valve 12 therein for regulating the amount of fluid coming through the pipe and for shutting it off altogether. Different fluids can be used in this device, but I prefer to use water, although compressed air might be used. The pipe 11 has a portion 12^a thereon on which slides a collar 13, the collar being fastened to a cup-shaped holder 14, which holder is open at its front end, this open front end being adapted to receive a ring 15, preferably made of rubber, although I am not confined to rubber, and from which project the vibratory elements 16 in the shape of small studs or posts made of rubber or similar elastic material or any material subject to vibration. The studs are normally without vibration, but are set in motion by the intermittent contact with each vibratory element of a stream of fluid passing through the pipe 11. To deliver this stream I mount a rotating nozzle 17 in the end of the pipe by any usual connection, providing said nozzle with outlets 18 which are so disposed that they are curved slightly in order to give the stream of water power to turn the nozzle, and also curved outward to deliver the streams emerging from these outlets in the direction of the vibratory elements.

The point of contact of the stream is adjustable by changing the relative positions of the vibratory elements and the nozzle, this being best accomplished by means of the sliding collar 13 on the portion 12^a of the pipe, the collar being fastened in its desired positions by a set-screw 19. When the collar is slid well back and fastened, the stream from the outlets 18 will hit the vibrating elements at a point indicated by the line *a* in Fig. 1 which would give a great deal of vibration to these elements on account of its impact coming at a point removed from the base of the studs or elements 16. If the cup-shaped holder is slid forward part way the stream would be de-

livered as indicated by the line *b*, causing less vibration than when the stream was delivered at the point indicated by the line *a*. A further sliding forward of the holder 5 would cause the stream to be delivered along the line indicated at *c* where a very slight vibration would be the result. In this way I regulate the point of impact of the stream against the vibratory elements and thus vary 10 the amount of vibration. The front of the nozzle is closed as at 20, being provided with small holes 21 for delivering a set of small jets of fluid against the surface on which the vibrator rests within the edge of 15 vibrating elements.

I do not wish to be understood as limiting myself to a revolving nozzle, since other means may be employed for directing a stream intermittently against each vibratory 20 element. In the case of the vibrating nozzle each stream as it rotates hits the vibratory elements successively so that each individual element is subjected to an intermittent stream which causes it to vibrate, 25 the vibration depending, as before stated, on the point of impact.

I have found that the use of hot water in some cases in combination with the vibrator, the hot water performing both the functions 30 of the heating element and a vibrating means, is advantageous. The particular form of vibratory element is not limited to the form shown, but one modification is illustrated in Fig. 2 where the ring 15 is 35 provided with thin vibratory loops 22 in lieu of the studs 16. The means of fastening the ring 15 to the end of the cup-shaped holder 14 is shown by means of the frictional contact of the ring 15, which is made 40 usually of elastic material, with the cup-shaped holder, but other fastening means can be employed for detachably fastening the vibratory elements to the holder.

A modified form of construction is shown 45 in Figs. 3 and 4, the pipe 12^b having a cup-shaped holder 23 thereon, and a rotary nozzle 24 is on the end of the pipe 12^b. The cup-shaped holder 23 can slide on the pipe 12^b and is fastened by means of a set-screw 50 25. On the mouth of the cup-shaped holder is a suitably formed spider 26 forming a center bearing 27 on which is fastened a resilient disk 28, made preferably of rubber, the disk being fastened at the bearing 55 27 and having its ends free to vibrate, being provided with suitable vibrating elements 29. The revolving stream of fluid from each outlet 30 of the nozzle 24 is directed on the back of the disk to successively engage the rear or base of each element 29. When the cup-shaped holder is 60 in the position shown in Fig. 4 the contact of the stream will follow the path indicated by the line *d*, that is, at the edge of the disk, 65 to cause a strong vibration of the vibrating

elements. If the cup-shaped holder is slid back the stream of water will hit the disk 28 at a point indicated by the line *e*, that is, closer to the base or the support of the disk 28 and the vibration will be less.

This device is economical, is cheap to make, is positive in its operation and has no parts that will be apt to get out of order.

I do not wish to be limited to the particular form of device herein shown, wishing to cover herein a vibrator consisting of vibrating elements which are caused to vibrate by being intermittently engaged by a stream of fluid.

Having thus described my invention, what I claim is:—

1. A vibrator comprising a holder, a vibratory element on the holder, and means for intermittently directing a continuous stream of fluid on the vibrator element to cause its vibration.

2. A vibrator comprising a holder, a series of vibratory elements on the holder, and a nozzle adapted to successively subject the elements to a stream of fluid.

3. A vibrator comprising a holder, a vibratory element on the holder, means for intermittently directing a stream of water on the vibratory element, and an adjusting means for changing the point of the impact of the stream on the element.

4. A vibrator comprising a holder, a series of vibratory elements on the holder, a nozzle for successively directing a stream of fluid on the elements, and means for adjusting the elements toward and from the nozzle to change the point of impact of the stream on the elements.

5. A vibrator comprising a holder, a pipe in the holder, a set of vibratory elements on the edge of the holder, and a rotating nozzle in the holder, said nozzle so directing a stream of fluid that it successively engages the vibratory elements.

6. A vibrator comprising a holder, a pipe in the holder, a set of vibratory elements on the edge of the holder, a rotating nozzle in the holder, said nozzle so directing a stream of fluid that it successively engages the vibratory elements, and an adjusting means for changing the relative positions of the elements and the nozzle to change the point of impact of the stream.

7. A vibrator comprising a pipe, a holder on the pipe, a series of vibratory elements on the edge of the holder, a rotating nozzle with outlets to deliver streams of water on the vibratory elements, the holder being adjustable on the pipe to move the elements toward or from the nozzle, and means for securing the holder in its adjusted positions.

8. A vibrator comprising a pipe, a holder slideable on the pipe, means for securing the holder in its adjusted positions on the pipe, a series of vibratory elements on the holder.

and a nozzle adapted to direct a stream of fluid so as to successively engage the elements in an oblique direction. 10

9. A vibrator comprising a pipe, a holder 5
slidable on the pipe, means for securing the holder in its adjusted positions on the pipe, a series of vibratory elements on the holder, a nozzle adapted to direct a stream of fluid so as to successively engage the elements in

an oblique direction, and means for detachably securing the elements to the holder.

In testimony, that I claim the foregoing, I have hereunto set my hand this 31st day of January, 1912.

HENRY BEHM.
